L. N. Gillis

ATTORNEY.

UNITED STATES PATENT OFFICE.

LEONARD SARGEANT, OF FAIRMONT, WEST VIRGINIA.

ONE-PIECE RAIL TIE.

Application filed November 20, 1923. Serial No. 675,922.

To all whom it may concern:

Be it known that I, LEONARD SARGEANT, a citizen of the United States, residing at Fairmont, in the county of Marion and 5 State of West Virginia, have invented certain new and useful Improvements in One-Piece Rail Ties, of which the following is a specification.

This invention relates to a one-piece rail tie, particularly adapted for use on tram roads that are temporarily laid in coal mines or other industrial plants where it is desirable to occasionally move the road, including the ties, to new positions.

15 One of the objects of the invention is to produce a one-piece tie. This is very desirable in constructions of this character since there are no loose parts to be lost in disassembling and assembling the tram road.

Another object of the invention is to produce a tie of any suitable shape forged from a single piece of metal at the smallest cost and with the least expenditure of time 25 and labor.

With these and other objects in view which will appear as the description proceeds, the invention consists in the novel features hereinafter described in detail, illustrated in the accompanying drawings, and more particularly pointed out in the appended claims.

Referring to the drawings:

Figure 1 is a top view showing two ties 35 with rails clamped thereon.

Fig. 2 is a side view of one end of a tie and the manner in which it clamps the rail.

In the drawing 1 represents a tie and 2 the rails. Each tie comprises a body portion between its ends, and near one end a clip 3 may be forged or otherwise produced in the tie by doubling up a portion of the tie and then looping the bent up portion 40 over to one side to form the clip 3 adapted to hold the portion 4 of an ordinary rail flange, the rail resting on the portion 45 of the tie.

The portion 5 is continued beyond the 50 rail flange and bent up to form a loop 6. To strengthen the tie, it may be provided with flanges 7 or the flanges may be omitted if desired.

Between the loop 6 and the upstanding web

of the rail a wedge block 8 may be driven 55 to securely hold the rail to the tie, the wedge block resting against the web 9 of the rail and ordinarily on the flanged portion 10 thereof and in the hollow of the loop 6.

To disassemble a tram road constructed in accordance with my invention, it is only necessary to drive out the wedge block 8 with a hammer or other suitable instrument and then moving the rail to the left 65 in Fig. 2 when the rails may be lifted off the ties.

It will be observed that my tie is already in one piece, there being no separable parts to get lost or misplaced when the road is 70 taken up to be removed to another position as is common in this kind of tram road.

The advantages of the construction are apparent to those skilled in the art and need not be further specifically pointed 75 out.

What I claim is:

1. A wide flat tram road tie having its entire body portion bent near one end to form a clip to extend over and come in contact with the top of the flange of a rail but terminating some distance from the web of the rail, the end of the tie being bent upwardly, then inwardly toward the rail to form a loop and a wedge block 80 adapted to rest in the loop partly under the end of the tie and above the rail flange to hold the rail flange in the embrace of said clip.

2. A tram road tie comparatively wide and flat on its top and having flanges on either side to strengthen the flat tie and to extend into the ground beneath the tie, said tie having its entire body portion bent near one end to form a clip to extend over and come in contact with the top of the flange of a rail, but terminating some distance from the web of the rail, the end of the tie being bent upwardly and inwardly toward the rail to form a loop, and a wedge block resting in the loop partly under the end of the tie and above the rail flange to hold the rail flange in the embrace of said clip.

In testimony whereof I hereunto affix my 105 signature.

LEONARD SARGEANT.
